[57] CLAIM

The ornamental design for a housing for a plurality of emitters for detectors, as shown and described.

DESCRIPTION

FIG. 1 is a front perspective view of a housing for a plurality of emitters for detectors;

FIG. 2 is a front view of the housing for the emitters for detectors, as shown in FIG. 1;

FIG. 3 is a rear view of the housing for the emitters for detectors, as shown in FIG. 1;

FIG. 4 is a side view of the housing for the emitters for detectors, as shown in FIG. 1;

FIG. 5 is a side view, opposite the side view shown in FIG. 4, of the housing for the emitters for detectors, as shown in FIG. 1;

FIG. 6 is a top view of the housing for the emitters for detectors, as shown in FIG. 1; and,

FIG. 7 is a bottom view of the housing for the emitters for detectors, as shown in FIG. 1.
